UNITED STATES PATENT OFFICE.

DARIUS H. PHILLIPS, OF OAKVILLE, WASHINGTON, ASSIGNOR OF ONE-HALF TO
WALTER S. FISK.

DESIGN FOR A COLLAR-BUTTON.

49,750.

Specification for Design.

Patented Oct. 10, 1916.

Application filed July 12, 1916. Serial No. 108,962. Term of patent 7 years.

To all whom it may concern:

Be it known that I, DARIUS H. PHILLIPS, a citizen of the United States, and a resident of Oakville, in the State of Washington, have invented a new, original, and ornamental Design for a Collar-Button, of which the following is a specification, reference being had to accompanying drawing, forming a part thereof.

Referring to the drawings, Figure 1 indi-

cates a plan of my device. Fig. 2 is a side elevation of same. Fig. 3 is an end elevation of my device including a curved back plate to which is secured an offset member which extends downwardly and at right angles to said curved plate.

I claim:

The design for a collar button as shown.

DARIUS H. PHILLIPS.
